(57) **CLAIM**

The ornamental design for a vehicle wheel, as shown and described.

DESCRIPTION

FIG. 1 is a front elevational view of a vehicle wheel showing my new design;

FIG. 2 is a rear elevational view thereof;

FIG. 3 is a left side elevational view thereof, the right side view being a mirror image of that shown;

FIG. 4 is a top plan view thereof, the bottom plan view being a mirror image of that shown;

FIG. 5 is a front perspective view thereof; and,

FIG. 6 is a rear perspective view thereof.

The subject vehicle wheel is installed in a vehicle such as a utility vehicle.
